D. R. WILLS.

CARBURETER.

APPLICATION FILED AUG. 12, 1915

1,263,501.

Patented Apr. 23, 1918.

UNITED STATES PATENT OFFICE.

DONALD R. WILLS, OF WASHINGTON COURT-HOUSE, OHIO, ASSIGNOR OF ONE-HALF TO
ADOLPH KLEIN, OF CINCINNATI, OHIO.

CARBURETER.

1,263,501.

Specification of Letters Patent. Patented Apr. 23, 1918.

Application filed August 12, 1915. Serial No. 45,113.

To all whom it may concern:

Be it known that I, DONALD R. WILLS, a citizen of the United States, residing at Washington Court-House, in the county of Fayette and State of Ohio, have invented 5 certain new and useful Improvements in Carbureters, of which the following is a specification.

My invention relates to carbureters used 10 in connection with explosive motors, and has for its object the provision of novel means whereby the feeding of fuel and air are automatically controlled by novel means for regulating the relative inflow of fuel 15 and air according to the speed of intake of the mixed fuel into the motor, and further to provide novel means whereby the intake of fuel may be regulated by the operator of the machine during its operation and auxiliary to the automatic control, so that the 20 correct mixture of fuel and air may be obtained as desired, according to the conditions under which the motor is running.

The invention will be further readily understood from the following description and claims, and from the drawing, in which latter:

Figure 1 is a central axial section of my improved device, taken on the line 1—1 of 30 Fig. 3.

Fig. 2 is a side elevation of my improved device.

Fig. 3 is a plan view of the same.

Fig. 4 is a cross-sectional detail, taken 35 on the line 4—4 of Fig. 1.

Fig. 5 is a cross-sectional detail, taken on the line 5—5 of Fig. 1.

11 represents the casing, and 12 the fuel-reservoir. The upper end of the latter is 40 seated in an annular seat, 13, of the casing, and is held toward said seat by a thimble, 14, which serves as a bolt having threaded connection 15 with the wall of the primary mixture passage 16, a compressible washer 45 17 being located between the head 18 of the thimble and an opposing seat 19 at the lower end of the fuel-reservoir.

21 represents a primary air-inlet passage, instanced as located in the thimble 14. A 50 fuel-valve 22 is located in the primary air-inlet adjacent to the constricted portion 23 of the passage, for directing the air received through the primary air-inlet past the fuel-valve in order to draw the fuel, such as gaso-

lene, through said valve, whereby a primary fuel-mixture is provided. This primary fuel-mixture is arranged to pass through the primary mixture passage 16, and thence through the outlet or suction-passage 24, which communicates with the 60 manifold or other fuel-mixture intake of the explosive motor to which the carbureter is connected, for instance, the internal combustion motor of an automobile.

A throttle-valve 25, is located in the suction-passage 24 and has suitable connection with an ordinary throttle-lever, instanced at 26. The throttle-lever may coact with a gage 27. The throttle-lever is suitably connected with the throttle-valve, as by being 70 articulated at 28 to a rod 29, which is articulated at 30 with an arm 31, rigidly secured to the rock-shaft 32 of the throttle-valve.

The fuel-valve in the present exemplification comprises a tube 36, in which there is 75 a valve-seat tube 37, provided with a valve-seat 38, with which the valve 22 coacts. The tube 36 connects with the oil-reservoir by means of ducts 40, forming a bridge-piece surrounded by the primary air-inlet 80 passage. The ducts 40 connect with a cavity 41. The valve-seat tube 37 extends through said cavity and the tube 36 and has a fuel-passage 42 therein which communicates with the ducts 40 by means of a passage or 85 passages 43 through the wall of said tube.

An internally and externally threaded nut 45 is received in the threaded opening 46 in the lower extension 47 of the thimble, and forms close union between said nut and 90 lower extension for preventing the leakage of fuel past the nut. The valve-seat tube is extended as a bolt having threaded connection 49 with the externally and internally threaded nut 45. A gasket-packing 95 50 is secured between the lower threaded end 51 of the nut 45 and the shank of the valve-seat tube, for preventing leakage of fuel between the latter and said nut 45.

The valve-seat tube is under manual control of the operator of the motor or machine during operation, for accomplishing which, in the present exemplification, an arm 54 is rigidly secured to the lower end of the valve-seat tube, accomplished in the 105 present instance by the threaded connection 55 between said arm and the lower threaded end 56 of the valve-seat tube and a nut 57,

forming a lock-nut between said arm and valve-seat tube.

The arm 54 is connected with a suitable lever, for instance a hand-operated lever 58, located in suitable convenient location at the operator's position, so that the fuel-valve-seat may be readily operated by the operator during running of the machine.

This is instanced as accomplished by means of a rod 59, articulated by articulation 60 with the arm 54, and connected with the lever 58 by articulation 61, the lever being pivoted on a pivot 62 and coacting with a gage 63, for gaging the extent of the movement of the manually movable member of the fuel-valve, in either direction, when this is desired.

The movement of the arm 54 in one direction will cause a movement of the valve seat 38 toward its coacting valve for diminishing the feeding of fuel to the mixing-passage, and employed for instance when a poorer mixture, that is to say, a mixture less rich in gasoline, is momentarily or otherwise desired during the running of the machine.

When the arm 54 is moved in the opposite direction, the valve-seat 38 is moved away from the coacting valve 22 for feeding a richer mixture to the mixing passage, that is to say, a mixture richer in gasoline, when such mixture is desired during the running of the machine in order to provide the correct mixture for the running conditions. These movements of the valve-member are accomplished to the desired extent for regulating by diminution or addition to the fuel of the mixture passing to the engine, irrespective of the momentarily coacting position of the valve.

The valve 22 is on a valve-stem 64, provided with a head 65, movable in a recess 66, the valve being guided by the wall of the recess and a bearing 67. A spring 68 is located in the recess 66 between the bottom of said recess and the head 65, for raising the valve-stem so that its head will coact with a heel 69 of a lever 70 pivoted by bearings 71 on a pin 72 located in a bearing 73 of the casing.

An automatic air-intake regulator 75 is located in an auxiliary air-intake passage 76, having a converging wall 77, converging at an angle to the line of movement of the automatic air-intake regulator, so as to increase the area of air-opening as the regulator is depressed by the suction of the motor. The inclination of the wall may be changed to suit the effective power or suction capacity of the motor. I prefer to accomplish this variation or adjustment by providing interchangeable walls for the auxiliary air-intake passage. One of these interchangeable walls is shown at 77 which has threaded connection 78 with the outer wall 79, which latter is instanced as forming the

support for the interchangeable wall. A wall having a different inclination is indicated in dotted lines as 77^a and another at 77^b as in Fig. 1.

The passage 76 communicates by a passage 80 with the primary mixture-passage 16, passing the same and augmenting the air-contents of the fuel-mixture passing to the throttle-valve.

The automatic air-intake regulator 75 is shown in the form of a disk, and is provided with a sleeve 81, which has bearing about a post 82, rigidly secured to the casing, as by the threaded connection 83 and lock-nut 84.

To prevent turning of the regulator and the parts mounted thereon, it is provided with a pin 87 on a screw 88, the pin extending into a slot 89, extending lengthwise of the post. A spring 91 surrounding the post and located between the bottom of the casing and the regulator 75, normally maintains the regulator in raised position, the limit of rising movement of the regulator being instanced as determined by the pin 87 striking the upper wall of the slot 89.

A guide 95 is pivoted on a lug 96 of the regulator 75 by means of a pin 97, extending through said lug and lugs 98 on the guide. A spring 99 located about a boss 100 on the regulator and the heel 101 of the guide 95, urges inclination of said guide toward the post 82. A screw 105 is threaded in a threaded lug 106 upon the sleeve 81, and has a notched head 107, the notches 108 of which coact with a knob 109 on the guide for holding the screw in adjusted positions, the position of the screw determining the inclination of the guide with relation to the line of movement of the regulator 75.

A shoe 110 on the lever 70 rides on the guiding face of the guide 95, for controlling the position of the valve 22 according to the positions assumed by the automatic air-intake regulator 75. If the guiding face of the guide 95 is parallel with the line of movement of the regulator 75, there will be no effect on the position of the valve 22 during movement of the regulator 75. If, however, the movable end of the guide is inclined toward the axis of the regulator 75, as instanced in Fig. 1 of the drawing, by the positioning of the screw 105, then the farther the regulator 75 is drawn inwardly by the suction of the engine, the greater will be the extent to which the valve 22 is moved away from the valve-seat 38 by the action of the spring 65.

The quickly repeated suction-intakes by the engine result in pulsations of the regulator. The regulator 75 is throughout its movements spaced from its coacting converging wall 77 so that air may at all times pass said regulator to the engine even at highest engine speeds, and so that said regulator may constitute a floating member at said

automatic air-intake, the air-intake space increasing gradually with the extent of movement of the regulator.

111 is a cap, having a cavity 112 therein, which acts as a buffer on depression of the regulator 75. To supplement this buffer I provide a piston 113 in a cylinder 114 in the post 82, the cylinder being shown closed by a threaded cap 115. A rod 116 extends 10 through a passage 117 in the post and has releasable connection at its upper end with the cap, as by being provided with a collar 118, the threaded end 119 of the rod passing through a hole in the cap 111, a nut 120 holding the rod in place. A heavy oil fills 15 the cylinder 114, there being slight space between the piston and the wall of the cylinder to permit the movement of the piston lengthwise on the cylinder but retard said movement for cushioning the regulator 75.

The fuel in the fuel-reservoir 12 is replenished from a suitable passage 124, in which there is a valve-seat 125, with which a float-valve 126 coacts.

25 The float-valve is controlled by a float-lever 127 pivoted at 128, and provided with a float 129.

By means of my improved device the richness of the fuel-mixture is under continual 30 manual control of the operator during the operation of the machine regardless of the position of the regulator 75 and irrespective of the position of the automatically movable member of the fuel-valve. The term manual 35 is employed as including control by the hand, foot or other human control.

By means of my improved device further, the operator may during running of the machine temporarily supply a greater ratio of 40 gasoline, as when running with a cold motor, or may temporarily supply a richer or leaner fuel-mixture if he finds this desirable for any reason at any given speed.

My improved device further provides an 45 extremely delicate adjustment for obtaining correct fuel-mixtures at great variations of motor-speed. For instance, the adjustment of the guide and consequent adjustment of the fuel-valve, is especially serviceable for obtaining the correct fuel-mixtures 50 for high motor-speeds, during which extreme movements of the regulator 75 takes place, while the adjustment of the valve-seat provides a delicate adjustment for ob-

taining correct fuel-mixtures for comparatively low speeds, the two adjustments combined providing delicately adjusted graduations of fuel-supply for all speeds.

It is of course obvious that changes may be made in the details shown and described 60 in the present exemplification of my improved device without departing from the spirit of my invention.

What I claim as new and desire to secure by Letters Patent is:

1. In a carbureter, the combination of a fuel-valve, a primary air-intake passage coacting therewith, an automatic air-intake regulator, a guide, a fixed pivot connecting one of the ends of said guide to said regulator, an adjusting screw adjustable on said regulator, said adjusting screw and the other end of said guide provided with coacting positioning parts for holding said screw in adjusted positions and for locating said 75 guide, a spring acting on said guide for causing coaction of said positioning parts and maintenance of adjusted position of said guide, a lever having a part coacting with said guide and a part coacting with 80 said fuel-valve and constructed and arranged for automatically regulating said fuel-valve according to the automatic movements of said automatic air-intake regulator.

2. In a carbureter, the combination of a 85 fuel-valve, a primary air-intake passage coacting therewith, an automatic air-intake regulator, a lever actuating said valve, a guide having lengthwise movement arranged to actuate said lever, said guide pivoted 90 to said regulator, an adjusting screw on said regulator having a head provided with positioning parts, said guide having a positioning part thereon coacting with said first-named positioning parts for positioning the 95 inclination of said guide with relation to the line of movement of said regulator and for locking said adjusting screw, and resilient means for causing coaction of said positioning parts.

100 In testimony whereof, I have signed my name hereto in the presence of the two subscribing witnesses.

DONALD R. WILLS.
